UNITED STATES PATENT OFFICE.

JAMES M. SCROGIN, OF MARE ISLAND, CALIFORNIA.

DESIGN FOR A MEMORIAL PIN.

52,196.

Specification for Design.

Patented July 16, 1918.

Application filed March 29, 1918. Serial No. 225,604. Term of patent 3½ years.

To all whom it may concern:

Be it known that I, JAMES M. SCROGIN, a citizen of the United States, residing at Mare Island, in the State of California, have invented a new, original, and ornamental Design for Memorial Pins, of which the following is a specification, reference being had to the accompanying drawing, forming part thereof.

The figure is a plan view of the memorial pin, showing my new design.

I claim:

The ornamental design for a memorial pin, as shown.

JAMES M. SCROGIN.

Witnesses:

LEO I. CAVANAUGH,
GEO. F. WELLER.
